UNITED STATES PATENT OFFICE.

WILLIAM H. SIKMA, OF OAKGLEN, ILLINOIS.

CUTTING AND BUNCHING DEVICE.

1,382,022.

Specification of Letters Patent. Patented June 21, 1921.

Application filed February 26, 1921. Serial No. 447,962.

To all whom it may concern:

Be it known that I, WILLIAM H. SIKMA, a citizen of the United States, and a resident of Oakglen, in the county of Cook and State 5 of Illinois, have invented certain new and useful Improvements in Cutting and Bunching Devices, of which the following is a specification.

My present invention relates to devices 10 for cutting and bunching stalked vegetables, such as asparagus, onions, carrots and the like, preparatory to putting same upon the market.

The primary object of my invention is to 15 provide a device which will enable a single operator to efficiently cut to size and bunch a great quantity of such vegetables in the shortest possible time.

Other objects and advantages will appear 20 to those skilled in this art as the description proceeds and with reference to the accompanying drawings.

My invention consists in a table-like structure supported upon legs in such a manner 25 that the table top slopes downwardly and backwardly toward the rear left corner thereof. A cradle is supplied at the left edge of the table substantially equaling the desired size of a bunch of stalks. Means 30 are provided to regulate the length of said bunches which are severed by means of a knife actuated by the operator's foot. Additional means are provided to retain the cut bunch in shape while tying with tape or the 35 like.

In the drawings, which are illustrative only of a preferred form of device:

Figure 1 is a front elevation of the device.

Fig. 2 is an end view of the same.

Fig. 3 is a top plan view showing the cutter and associated mechanism.

Referring now more particularly to the drawings in which like numerals designate 45 like parts throughout the several views, the invention consists of a table top shown at 1, suitably supported upon legs 2 in such a manner that the part 1 slopes backwardly and downwardly toward the rear left corner 50 for a purpose more fully hereinafter described.

Brace rods 3 are utilized to stabilize legs 2 at the bottom and members 4 not only tie the front and rear legs together but aid in 55 supporting the top 1. These members extend rearwardly a considerable distance in

order that the crates of vegetables being brought from the field may be rested thereon within easy reach of the operator.

Table top 1 is provided with a side wall 5 and rear wall 6, said rear wall extending beyond the left edge of top 1 as shown at 6a. The part 1 and rear wall 6 are preferably covered with sheet metal 7 or the like, which facilitates cleaning and makes the device more durable.

At the left edge of top 1 a rack or cradle is provided which consists preferably of two substantially U-shaped metal straps 8 secured between the top of the table and the metal covering 7. The U-shaped portions are of a size to contain the number of stalks required to make up a bunch desired for any particular market. The metallic covering 7 upon rear wall 6 extends beyond and below the left edge of top 1 to a point slightly beyond and below the straps 8. The overhanging part of this covering is secured to the rear wall in a loose manner as by bolts 9 which allow a front and back movement 80 of the covering to take place. Wedges 10 or the like of various thicknesses are adapted to be inserted between covering 7 and rear wall 6 at the overhang of the covering which will determine into what lengths the 85 stalks held in members 8 will be cut. By removing or adding wedges, the length of the stalks may obviously be varied as desired.

A trough-like structure secured under the 90 left edge of top 1 and cradle 8 is composed of bottom 11, rear wall 12 and front wall 13. A knife 14 mounted upon a carrier 15 is adapted to travel close to the front edge of the front strap 8, and is inclined to the 95 plane of the table top which gives a sweeping action when the knife is actuated to cut the stalks. The blade 14 is preferably secured to the carrier by means of bolts 16 which permit of easy removal when it is 100 desired to sharpen the knife or replace the same.

Carrier 15 is journaled in the bottom 11 of the trough and also in a step extension 17 attached to one of the front legs 2. A pedal 105 18 is hinged as at 19 to the rear cross-brace 3. Any suitable flexible connection 20 may be made between the pedal and the carrier 15. A coil spring 21 encircles carrier 15, bearing downwardly upon step 17, its upward spring being limited by a stop 22 upon the carrier 15.

A guard or sheath 23 is provided for the knife which is shown as being mounted upon a rear extension 24 of the front wall 13 of the trough member.

5 A cylindrical member 25 is mounted perpendicular to portion 6^a and is provided with a longitudinal groove 26 on its upper surface. The diameter of this member is slightly larger than the desired diameter of 10 a bunch of stalks. A plurality of rubber bands or the like are shown at 27 encircling member 25 for a purpose more fully herein-after described.

The operation of the device is as follows: 15 A crate of asparagus, onions, carrots or the like, is brought from the field having the tips or heads as the case may be arranged in one direction. This crate is deposited upon the extensions of the top braces 20 4. The operator standing in front of the table places a quantity of the vegetables upon the top 1 making sure the heads or tips are substantially touching rear wall 6. The backward inclination facilitates keeping the 25 stalks even on one side. A number of stalks are now swept into cradle 8 aided by the sloping table top. The operator grasps the bunch in the cradle in his left hand, presses downwardly on pedal 18 which cuts the 30 bunch into the required length, wedges 10 having been properly adjusted previously. The spring 21 insures the return of the knife blade to its sheath and the waste material falls onto the bottom 11 of the trough and 35 into a suitable receptacle. The bunch still grasped by the operator is removed from the cradle and inserted partially into member 25 and a rubber band snapped upon the bunch with the right hand. The bunch is then in- 40 serted farther into member 25 and another band applied. The groove 26 facilitates removal of the bands by inserting the finger nail between the band and member 25. The bunch is now secured together and may be 45 further tied with tape or the like if desired, the bands serving to hold the bunch securely while the tape is applied.

It will be readily apparent that this device simplifies the cutting and bunching of stalk 50 vegetables to a considerable degree as a single operator may readily compete with several working in the old way.

It will be seen that this device may be used efficiently with any articles of a stalk 55 or rod nature which are to be cut into proper lengths and bunched, and therefore, I do not wish to be limited to a device for cutting and bunching vegetables.

Obviously various modifications may occur to those skilled in this art without de-

parting from the spirit of my invention, but what I claim is:

1. The device of the character described comprising a table supported upon legs, provided with a cradle below one of its edges 65 and a knife mounted in a plane transverse to said edge.

2. The device of claim 1, said table sloping downwardly toward the cradle edge and backwardly. 70

3. The device of claim 1, said table being provided with a rear wall, a covering therefor, and means for adjusting the proximity of said covering to the knife blade. 75

4. The device of claim 1, said table being provided with a rear wall, a covering therefor, means for adjusting the proximity of said covering from the knife blade including a wedge inserted between said covering and said rear wall. 80

5. The device of claim 1, said table being provided with a rear wall, a covering therefor and means to space said covering from said rear wall. 85

6. The device of claim 1, said table being provided with a rear wall, and a covering therefor, said covering extending beyond and below said table. 90

7. The device of claim 1, said table being provided with a rear wall, and a covering 95 therefor, said covering extending beyond and below said table, a portion of said covering being flexible.

8. The device of claim 1, said table being provided with a rear wall, a covering therefor, said covering extending beyond and below said cradle. 95

9. The device of claim 1 provided with a trough beneath the cradle, and a sheath for said knife mounted upon said trough. 100

10. The device of claim 1, provided with a carrier for said knife, said carrier including a U-shaped member, one leg of which is longer than the other. 105

11. The device of claim 1, said knife being provided with a carrier, a trough mounted beneath said cradle, said knife carrier being journaled in said trough.

12. The device of claim 1 provided with a sheath for said knife, a step extension on 110 a table leg, means to insure the return of the knife to said sheath, said means engaging said step extension.

13. The device of claim 1, said knife being mounted upon a carrier, means to impart 115 automatic movement to said knife, said means partially encircling said carrier.

In testimony whereof I affix my signature.

WILLIAM H. SIKMA.
